INVENTOR:
By Axel Orling
Mr Wallace White
ATTY.

UNITED STATES PATENT OFFICE.

AXEL ORLING, OF LONDON, ENGLAND.

TELEPHONE RECEIVER.

Application filed October 12, 1922. Serial No. 593,950.

To all whom it may concern:

Be it known that I, AXEL ORLING, subject of the King of Great Britain, residing at No. 47 Victoria Street, Westminster, London, S. W. 1, England, have invented new and useful Improvements in Telephone Receivers, of which the following is a specification.

This invention relates to telephone receivers and its object is to enable a very cheap construction of telephone receiver to be made.

I have discovered that a diaphragm of a telephone receiver, instead of being a separate plate anchored around its periphery, may form an integral portion of another structure, such as the cover of the casing or the casing enclosing the receiver bobbin.

Hence, according to the invention, the diaphragm of a telephone receiver is constituted by the plane portion of a shallow cylindrical sheet iron casing, serving either as a cover or lid closing a shallow cylindrical box enclosing the receiver bobbin, or constituting the enclosing box itself.

Telephone receivers according to the invention are illustrated by way of example on the accompanying drawing, in which:—

Fig. 1 is a side elevation, partly in section, of one form of construction.

Fig. 2 is a longitudinal section of another form of construction.

Fig. 3 is a side elevation of a further modification.

Figs. 4 and 5 are a longitudinal section and a sectional plan respectively of still another modification.

a is an ordinary shallow stamped tin plate box, having a shouldered cylindrical portion, over the portion of reduced diameter *a'* of which fits the stamped perpendicularly flanged tin plate lid *b*.

c is the receiver bobbin which is contained in the box *a*.

d is a wide hole is formed centrally in the base of the box *a*, and the bobbin *c* contained within the box is secured by a screw *d*, constituting the core of the bobbin *c*, to a magnet *e*.

In the construction shown in Fig. 1, the magnet *e* is a bar magnet extending axially from the box *a*, which latter is magnetically insulated from the box by brass or other non-magnetic washers *f*, *g*, bearing one on each side of the border of the wide hole in the base of the box *a*.

The leads *h* covered with small rubber tubing *i* to protect same are led through a hole in the box *a*.

After assembly of the various parts, the lid *b* is point soldered or otherwise secured to the body of the box *a*, to prevent displacement therefrom.

The correct degree of separation of the core *d* of the bobbin *c* from the lid *b* of the box, which lid constitutes the telephone diaphragm, may be predetermined, for instance as follows:—

On assembly of the parts a piece of paper is interposed between the end of the core *d* and the inner face of the lid *b*, and the latter is fitted in tight contact with the paper, without however distortion of either the box *a* or the lid *b*. Then after the lid *b* has been secured on the box *a* by soldering, by pulling the magnet *e*, the core *d* attached thereto is drawn slightly away from the lid *b*, the base of the box *a* being temporarily bulged outwards, allowing the piece of paper to drop or be shaken off the end of the core *d*. On relaxing the pull on the magnet *e*, the core *d*, owing to the bulged base of the box *a* regaining its flat condition, approaches the lid *b* but is separated therefrom by the amount of the thickness of the previously interposed piece of paper. Thus a definite degree of separation of the core and diaphragm is assured.

Instead of a predetermined degree of separation of the diaphragm from the core, the distance between same may be adjustable. Fig. 2 illustrates a construction in which this is effected. The core *d* is of such length as to touch or nearly touch the surface of the lid *b* when the base of the box *a* is unstrained. The outside washer *g* is of larger diameter than the inside washer *f*, and between the peripheral portion of the outside washer *g* and the outer surface of the base of the box *a*, a packing ring *j* of large diameter is interposed. A tubular sleeve *k* of small diameter encloses the bar magnet *e* and bears by one end against the large outside washer *g*. The outer end of the enclosing sleeve *k* is closed by a small washer *l*, and a screw *m* passing through this latter washer screws into the outer end of the magnet *e* which terminates short of the washer *l*. On tightening the screw *m* the magnet *e* is drawn towards the outer end of the sleeve *k* and bulging outwards the base of the box *a*, within the area enclosed by the packing ring

j, withdraws the core *d* and bobbin *c* from the lid *b*, which latter constitutes the diaphragm.

5 The constructions shown in Figs. 3, 4 and 5 differ from that of Fig. 1 solely as regards the shapes of the magnet *e*.

10 In Fig. 3 the magnet *e* is a horseshoe magnet extending laterally from the box *a*. One pole arm of this magnet is secured to the core screw *d* whilst the other pole arm, which is shorter is bent round and passed through a hole in the side of the box *a* terminating short of the side of the bobbin *c*.

15 As shown in Figs. 4 and 5 the magnet *e* may be coiled and contained wholly within the box *a*, with one pole secured to the core screw *d* and the other pole is magnetically connected to the base of box *a* by a riveted iron washer *n*.

20 Obviously with a tin plate box, the base of the box instead of the lid may constitute the telephone diaphragm. Also with a tin plate lid serving as a diaphragm, the body of the box need not be of magnetic material, and 25 may be of non-magnetic sheet metal, wood or other suitable substance.

I claim:

1. In a telephone receiver, a bobbin, a core of said bobbin, a sheet iron box enclosing

30 said bobbin and core, a magnet having one pole connected to said core and the other pole in magnetic proximity to said box, and a sheet iron perpendicularly flanged lid of said box including a diaphragm in magnetic proximity to said core.

35

2. In a telephone receiver, a bobbin, a core of said bobbin, a sheet iron box enclosing said bobbin and core, a magnet having one pole connected to said core and the other pole magnetically connected to said box, and a 40 sheet iron perpendicularly flanged lid of said box including a diaphragm in magnetic proximity to said core.

3. In a telephone receiver, a bobbin, a core of said bobbin, a sheet iron box enclosing 45 said bobbin and core, a magnet in said box having one pole connected to said core and the other pole magnetically connected to said box, and a sheet iron perpendicularly flanged lid of said box including a diaphragm in 50 magnetic proximity to said core.

In testimony whereof I have signed my name to this specification in the presence of two subscribing witnesses.

AXEL ORLING.
